EDWARD R. KAST, OF BALTIMORE, MARYLAND.

SIGNATURE-HANDLING MECHANISM.

1,083,617.

Specification of Letters Patent.

Patented Jan. 6, 1914.

Application filed April 5, 1913. Serial No. 759,176.

To all whom it may concern:

Be it known that I, EDWARD R. KAST, of Baltimore, Maryland, have invented a new and useful Improvement in Signature-Handling Mechanism, which invention is fully set forth in the following specification.

The present invention relates to signature-handling mechanism, and particularly to mechanism for assembling and insetting signatures to form books or pamphlets.

In my application Serial No. 745,973, filed Feb. 3d, 1913, one important feature is the provision above the saddle of supporting members on which the signatures are either manually or mechanically deposited and from which they are removed onto the saddle by suitable means (usually pins) carried by the conveyer which moves along the saddle. The object of these supporting means was to insure accurate alining or "heading up" of the signatures on the saddle, it being pointed out that if the signatures are deposited directly on the saddle or on signatures carried by the saddle, the friction between the deposited signatures and the saddle, or the deposited signatures and the signature or signatures on which they are deposited, would be so great as to prevent the perfect alining of the various

signatures of each group; whereas if each signature is deposited on a supporting member above the saddle from which it can be readily removed when engaged by the pins on the conveyer, it will be in proper engagement with the pin, and therefore properly alined when it falls on the saddle or on the group of signatures with which it is inset.

While, owing to the small amount of friction between the signatures and the supporting members, the former can be readily removed from said supporting members onto the saddle, and while, when the signatures are first deposited on the saddle, they are properly alined, it has been experienced that they do not remain so alined as the groups of signatures are progressed along the saddle. This is due to the fact that the friction is very great between the innermost signature of each group and the saddle, due to the fact that the signatures are entirely supported by the saddle; and, even though the signatures are alined when they are first removed from the supporting members onto the saddle, this friction causes each innermost signature to be "combed out", or, in

other words, to get out of alinement with the other signatures of the group, and to be crowded against the signature-engaging means that progresses each group along the saddle. Unless, therefore, the signatures of each group are again "headed up" or alined, before they are stitched, the innermost signature of each group will project slightly from the other signatures, and even though the books are trimmed, the printed matter on the pages will be out of register.

The object of the present invention is to prevent this "combing out" of the innermost signatures, and to insure that the signatures of each group are continually maintained in alinement. This is effected by practically eliminating the friction between the saddle and the signatures, so that, as the signatures are removed from the supporting members, they are alined by the pins or other signature-engaging means carried by the conveyer, and maintained in alinement.

The invention will be better understood by reference to the accompanying drawing which is a detailed perspective of one expression of the inventive idea.

Referring to the drawings, wherein like reference numerals indicate like parts, 10 is a support, here shown as a saddle, along which groups of inset signatures are progressed preferably to the mechanism for stitching the same, and preferably to mechanism for automatically delivering the same. At its apex, this saddle is provided with an opening or slot 11, under which travels a suitable carrier or conveyer, here shown as a chain 12. Secured to this chain 12 at regular intervals are a plurality of signature-engaging means, here shown as pins 16, said pins projecting upwardly through slot 11 far enough to engage the edge of the signatures that are deposited, either mechanically or manually, on signature-supporting means, here shown as fingers or strips 17, which are preferably adjustably mounted on brackets 18 secured to any suitable part of the frame of the machine 19.

Heretofore, the first signature removed from each finger or strip 17, of which any suitable number are provided directly above the saddle 10, by the pins 16, has fallen directly upon said support or saddle, practically the entire surface of each leaf of the signature being in intimate contact with its

respective face of the saddle. Each succeeding signature, as it was removed from the finger or support 17 by the finger 16 onto its appropriate signature already resting on the saddle, would be temporarily "headed up" or alined with the other signatures of the group, but, due to the large amount of friction between each innermost signature and the saddle, said signature would be "combed out", or, in other words, would get out of alinement with the signatures deposited thereon, said innermost signature being crowded against its pin 16. Unless, therefore, the groups of signatures were headed up or alined before they were stitched, the innermost signature of the book or pamphlet would slightly project beyond the other signatures of the book or pamphlet, thus causing the printed matter on the pages to be out of register.

I have discovered that the solution of the problem of maintaining the signatures of each group in perfect alinement, as the signatures are progressed along the saddle to the stitching mechanism, lies along the line of practically eliminating the friction between the innermost signature and the saddle, and in so depositing each succeeding signature of each group that its rear edge will be immediately above the rear edge of the signature on which it rests, the perfect alinement thus secured being maintained while the groups of signatures are progressed past the stitching mechanism.

I have effected the elimination of the friction between each innermost signature of each group and the saddle by the provision, between the fingers 16, of means carried by the conveyer 12, projecting upwardly through the slot 11, on which means the signatures which are removed from the fingers or strips 17 by the pins 16 are deposited, said means engaging the inside of the fold of each innermost signature. By reason of the fact that these means project above the saddle, air can freely pass between said innermost signatures and the saddle, with the result that said saddle acts simply to hold the signatures open, and to guide them as they are moved along to the stitching mechanism. Preferably, the means on which the signatures are deposited are a plurality of signature-supporting elements or projections secured to the chain 12 and projecting upwardly through the slot 11 in the saddle 10, but said elements or projections do not extend upwardly as far as the signature-engaging means or pins 16. The provision of such projections 20 has the advantage that any tendency of said innermost signatures to move longitudinally of the saddle 10 will be resisted by the engagement therewith of the plurality of points of said projections. It will be understood, however, that the signatures may be deposited upon

any other suitable means which will maintain the innermost signatures in proper relation to the support or saddle.

While, for the purpose of clearness, one embodiment of the inventive idea has been herein described and illustrated in detail, it is apparent that the invention is not restricted to the particular structural embodiment which is illustrated and described, but that it is susceptible of embodiments conforming to the definition of the invention given in the claims which follow.

What is claimed is:—

1. In combination, a support or saddle along which groups of signatures are conveyed, a supporting member arranged above said saddle on which supporting member signatures are deposited, a conveyer movable along said saddle, supporting means carried by said conveyer and projecting above said saddle, and signature-engaging means carried by said conveyer and removing the signatures from said supporting member onto said supporting means carried by the conveyer.

2. In combination, a support or saddle along which groups of signatures are conveyed, a supporting member arranged above said saddle on which supporting member signatures are deposited, a conveyer movable along said saddle, a plurality of projections carried by said conveyer and projecting above said saddle, and signature-engaging means carried by said conveyer and removing the signatures from said supporting member onto said plurality of elements carried by the conveyer.

3. In combination, a support or saddle along which groups of signatures are conveyed, a supporting member arranged above said saddle on which supporting member signatures are deposited, a conveyer movable along said saddle, a plurality of pins carried by said conveyer and projecting above said saddle, and signature-engaging means carried by said conveyer and removing the signatures from said supporting member onto said plurality of pins carried by the conveyer.

4. In combination, a support or saddle along which groups of signatures are conveyed, a plurality of supporting members arranged above said saddle on which supporting members signatures are deposited, a conveyer movable along said saddle, a plurality of pins carried by said conveyer and projecting above the saddle, and a plurality of signature-engaging means carried by said conveyer removing the signatures from said supporting members onto the pins carried by the conveyer.

5. In combination, a support along which groups of signatures are conveyed, a supporting member arranged above said support, on which supporting member signa-

tures are deposited, a conveyer movable along said support, supporting means carried by said conveyer and engaging the signatures above said support, and signature-engaging means carried by said conveyer and removing the signatures from said supporting member onto said supporting means carried by the conveyer.

6. In combination, a support along which 10 groups of signatures are conveyed, a supporting member arranged above said support, on which supporting member signatures are deposited, a conveyer movable along said support, supporting means mov-

able with said conveyer and engaging the 15 signatures above said support, and signature-engaging means carried by said conveyer and removing the signatures from said supporting member onto said supporting means movable with said conveyer.

20 In testimony whereof I have signed this specification in the presence of two subscribing witnesses.
